UNITED STATES PATENT OFFICE.

SAMUEL ROCKAFELLOW, OF MUSCATINE, IOWA, ASSIGNOR OF ONE-HALF
TO WILLIAM G. REEVE, OF PERU, ILLINOIS.

CAR-STARTER.

SPECIFICATION forming part of Letters Patent No. 319,029, dated June 2, 1885.

Application filed March 13, 1885. (No model.)

To all whom it may concern:

Be it known that I, SAMUEL ROCKAFELLOW, a citizen of the United States of America, residing at Muscatine, in the county of Muscatine and State of Iowa, have invented certain new and useful Improvements in Street-Car Starters, of which the following is a specification, reference being had therein to the accompanying drawings.

10 My invention relates to street-car starters in which the draw-bar is connected with a lever geared by a pawl and ratchet-wheel or other suitable mechanism to the axles or wheels of the car, so that the draft-power upon the 15 draw-bar is greatly augmented by lever-power, and is applied directly in favor of forward rotary movement of the wheels, enabling the car to be easily started. The draw-bar is connected with the clutching mechanism so as to 20 allow sufficient forward movement of the bar, before the power is applied to the car, to avoid the usual sudden strain and jerking movement.

25 Suitable devices are provided for returning the draw-bar and starting mechanism to their ordinary position after the car is started, and for locking the bar in position and preventing it from being drawn out too far in the starting operation; and the invention consists of the construction and combinations of these devices, 30 all as hereinafter fully set forth, and as claimed.

In the accompanying drawings, Figure 1 is a perspective view showing the frame and running-gear of a car with my improvements attached. Fig. 2 is a vertical longitudinal section. Fig. 3 is a section in front of the rear cross-beam of the frame, showing a rear elevation of the starting mechanism.

35 A designates the car-frame, and B the car-wheels. C is a draw-bar, the forward portion of which 40 is extended under the front cross-beam of the car, and is arranged to reciprocate in a bearing, a, bolted to the under side of the cross-beam. The front end of the draw-bar is provided with a draft ring or hook, b, and the 45 rear end of the draw-bar is jointed to the upper end of the lever D, the lower end of which is keyed onto one end of the rock-shaft E, which is placed in bearings a' on the bar F, 50 the ends of which bar are bolted to the hangers

b', attached to the under side of the side beams of the car-frame.

G is a lever, the lower end of which is keyed to the outer end of the rock-shaft.

H is an arm, the forward end of which is 55 jointed to the upper end of the lever G.

K is a ratchet-wheel rigidly attached to one of the axles, or to the hub of one of the wheels of the car.

L is a bifurcated lever provided with the 60 collars c, extended loosely around the hubs of the ratchet-wheel. The upper portion of this lever is hinged or pivoted to the rear end of the arm H. The lever L is provided with a pivoted pawl, d, constructed and arranged to 65 catch in the teeth of the ratchet-wheel.

M is a spring, one end of which is connected with the lever L, and the other end is attached to the car-frame, for the purpose of returning the draw-bar and connecting devices 70 to their ordinary positions after the car is started.

It is obvious that the invention or the operation of the starter does not depend upon any particular construction or location of the spring 75 employed to return the draw-bar and devices. Any suitable spring or other device may be employed, and may be located at any desired place. For example, the devices and bar may be returned by means of a weight attached to 80 one of the levers.

N is a spring rod or catch fastened at one end to the front cross-beam of the car-frame in position to spring into a notch, c', in the lower edge of the forward portion of the draw-bar, to hold it in position. The free end of this spring-rod is bent upward and extended through the car-floor, and has formed on it a foot-piece, f. The rear portion of the connecting-arm H is provided with a lug, h, to catch 85 over an upwardly-inclined lug formed on the pawl d, to hold it in a disengaged position from the ratchet-wheel when the draw-bar and its connecting devices are in their returned and ordinary position. The draw-bar is provided 90 with stop-lugs d', constructed to catch against the bearing a and stop the forward movement of the bar, to prevent it from being drawn out too far.

I do not limit my invention to the particu- 100

lar location and construction of the rock-shaft and connecting-levers. The principle of the invention would be the same if these devices were located farther forward or backward, and 5 geared to the front instead of the rear axles or wheels. Neither do I wish to be limited to the pawl and ratchet-wheel by which the power-lever is geared to the wheels or axles, it being evident that any other suitable mechanism 10 may be employed, by which the lever-power may be applied directly in favor of the forward rotary movement of the wheels.

The operation of my improved car-starter is as follows: In all cases when the car is to be 15 started, except on a downgrade, as soon as the brakes are loosened the driver places his foot upon the foot-piece *f* of the spring-rod *N*, pressing it downward out of the notch in the draw-bar, thus releasing it, and then the draft of 20 the horse or horses upon the draw-bar moves it forward, which moves the levers and rock-shaft, and throws the draft entirely upon the ratchet-lever, the forward movement of which releases the pawl *d* from the lug *h* on the 25 arm *H*, and allows the pawl to drop into the teeth of the ratchet-wheel. The draft, greatly increased in its power by the lever, is thus transferred to the car wheel or axle to which the ratchet-wheel is rigidly attached, and the 30 car is thus easily started, and the usual sudden jerk is entirely avoided by the forward movement of the draw-bar before the pawl engages the ratchet-wheel and the draft is applied to the car-wheel, and then the increased power 35 obtained by the levers enables the horse or horses to start the car without any severe strain upon them.

Having described my invention, I claim as new—

1. In a car-starter, the combination, with 40 the rock-shaft *E*, placed in bearings under the car-floor, the levers *D G*, rigidly attached to the ends of the rock-shaft, the ratchet-wheel *K*, attached to an axle or a hub of one of the 45 wheels of the car, the bifurcated lever *L*, provided with a pawl, *b*, and having collars *c* extended loosely around the ratchet-wheel hubs, and the connecting-arm *H*, jointed to the levers *G* and *L*, of the draw-bar *C*, having its lower 50 end connected with the lever *D*, and means, herein set forth, for locking and unlocking the draw-bar, and for returning the bar and connecting devices to their ordinary position, substantially as and for the purposes described.

2. In a car-starter, the combination, with 55 the rock-shaft *E*, the levers *D G*, the connecting-arm *H*, the bifurcated lever *L*, provided with the pawl *d*, and the draw-bar *C*, provided with the notch *j*, of the spring-rod *N*, extended upward and provided with the foot-piece *f*, 60 substantially as and for the purposes described.

3. In a car-starter, the combination, with 65 the draw-bar *C*, rock-shaft *E*, levers *D G*, ratchet-wheel *K*, bifurcated lever *L*, and pawl *d*, of the connecting-arm *H*, provided with the lug *h*, adapted to catch over the upper portion of the pawl and hold it out of gear, and allow the free forward movement of the draw-bar, substantially as and for the purposes described.

In testimony whereof I affix my signature in presence of two witnesses.

SAMUEL ROCKAFELLOW.
